UNITED STATES PATENT OFFICE

2,317,027

MULTIPLE FILAMENT ELECTRIC LAMP

Henry E. Butler, Scotia, N. Y., assignor to General Electric Company, a corporation of New York

Application April 18, 1942, Serial No. 439,602

8 Claims. (Cl. 176—26)

My invention relates to electric incandescent lamps and more particularly to multiple filament lamps.

An object of my invention is to provide a simplified multiple filament lamp wherein provision is made for readily replacing or substituting a second filament for a first filament. To this end the lamp preferably comprises means for removably supporting a filament and conducting current thereto, and a second filament which is so designed and supported in the bulb of the lamp that it may be transferred bodily onto the said supporting and current conducting means to replace the first-mentioned filament. One of the features of my invention is the provision of an arrangement whereby the said second filament may be transferred by means of a magnet. Further features and advantages of my invention will appear from the following detailed description of a species thereof and from the drawing.

In the drawing, Fig. 1 is a perspective view of a lamp comprising my invention, together with a magnet for transferring the second or auxiliary filament, and Fig. 2 is an elevation showing an alternative method of supporting a filament.

Referring to the drawing, the lamp comprises the usual glass bulb 10 and base 11. A pair of lead-in wires 12, 12 extend into the bulb through the press portion 13 of the usual stem 14, and are connected at their outer ends to the shell and end contacts of the base 11. The inner ends of the lead-in wires 12, 12 are provided with hooks 15, 15. A filament 16, preferably of tungsten, is supported by the hooks 15, 15. The said filament has straight end portions 17, 17 which engage the hooks 15, 15 and may consist of one of the metals commonly used for lead-in wires, although they may, if desired, be continuations of the filament itself. Attached to each end of the filament, or to the end portion 17 thereof, is a disc 18 of magnetizable metal such as steel.

A second filament 16' is also located in the bulb 10 and it may be similar in design to the filament 16. As shown in the drawing, the second filament 16' is merely disposed loosely within the bulb 10 and is supported by the bulb.

Upon failure of the filament 16, the second filament 16' may be transferred onto the hooks 15, 15 by means of a magnet 19 which acts on the magnetizable discs 18', 18'.

While I have shown and described one species of my invention, it will be obvious to those skilled in the art that various modifications may be made therein. It will be understood that, if desired, the filament 16' may be designed for a

lower or higher candle power than the filament 16, and the filaments 16' and 16 may be interchangeably mounted on the hooks 15, 15 to provide a lamp which emits different levels of illumination. To this end, the lamp may be provided with additional hooks, similar to the hooks 15, 15 for supporting the filament 16 when the filament 16' is to be substituted therefor in the hooks 15, 15.

As an alternative method of supporting the filament on the lead-in wires 12, 12, I may replace the hooks 15, 15 with small permanent magnets 20, 20 (Fig. 2) such as Alnico magnets, and make the end portions 17, 17 of magnetic metal. With such a construction, in the event the master magnet 19 is not available, the renewal filament 16' with its magnetic metal end portions 17', 17' may be placed on the faces of the small magnets by properly manipulating the lamp.

What I claim as new and desire to secure by Letters Patent of the United States is:

1. An electric incandescent lamp comprising a bulb containing a filament, means for removably supporting said filament and conducting current thereto, and a second filament in said bulb physically separate from said supporting and current conducting means and from said first mentioned filament and capable of being transferred bodily onto said supporting and current conducting means to replace said first-mentioned filament.

2. An electric incandescent lamp comprising a bulb containing a filament, means for removably supporting said filament and conducting current thereto, and a second filament in said bulb capable of being transferred bodily onto said supporting and current conducting means to replace said first-mentioned filament, said second filament having secured thereto members of magnetizable metal by means of which the filament may be picked up by an external magnet.

3. An electric incandescent lamp comprising a bulb, a pair of lead-in wires extending into said bulb and having hook-shaped end portions, a filament supported by said hook-shaped lead-in wire end portions without being secured thereto, and a second filament in said bulb spaced from said lead-in wire end portions and physically separate from said first-mentioned filament and capable of being transferred bodily onto said hook-shaped lead-in wire end portions to replace said first-mentioned filament.

4. An electric incandescent lamp comprising a bulb, a pair of lead-in wires extending into

said bulb and having hook-shaped end portions, a filament supported by said hook-shaped lead-in wire end portions without being secured thereto, and a second filament in said bulb capable of being transferred bodily onto said hook-shaped lead-in wire end portions to replace said first-mentioned filament, said second-filament having discs of magnetizable metal secured to its ends by means of which the filament may be picked up by an external magnet.

5. An electric incandescent lamp comprising a bulb, a pair of lead-in wires extending into said bulb and having hook-shaped end portions, a filament supported by said hook-shaped lead-in wire end portions without being secured thereto, and a second filament in said bulb capable of being transferred bodily onto said hook-shaped lead-in wire end portions to replace said first-mentioned filament, each of said filaments having discs of magnetizable metal secured to its ends by means of which the filaments may be picked up by an external magnet.

6. An electric incandescent lamp comprising a bulb containing a filament having end portions of magnetic material, means for removably

supporting said filament and conducting current thereto comprising permanent magnets engaging the said end portions of the filament, and a second filament in said bulb capable of being transferred bodily into engagement with said permanent magnets, said second filament also having end portions of magnetic material.

7. In an electric incandescent lamp, a filament having end portions of magnetic material, and 10 means for supporting said filament and conducting current thereto comprising permanent magnets engaging the said end portions of the filament.

8. The method of replacing one filament removably carried by supporting and current conducting means in the sealed bulb of an incandescent lamp with a second filament also located in the sealed bulb and carrying members of magnetizable metal which comprises bodily transferring the second filament onto the said supporting and current conducting means by means of a magnet located externally of the bulb to replace the first-mentioned filament.
